UNITED STATES PATENT OFFICE.

MARY FLORENCE POTTS AND JOSEPH H. POTTS, OF AUSTIN, ILLINOIS.

REMEDIAL OR MEDICAL APPLIANCE.

SPECIFICATION forming part of Letters Patent No. 468,946, dated February 16, 1892.

Application filed April 16, 1891. Serial No. 389,152. (No model.)

To all whom it may concern:

Be it known that we, MARY FLORENCE POTTS and JOSEPH H. POTTS, citizens of the United States, residing at Austin, Illinois, have invented certain new and useful Improvements in Remedial or Medical Appliances, of which the following is a specification.

This invention relates to the application of heat to parts of the human body as a counter-irritant in disease; and its object is to provide a convenient device for this purpose possessing superior advantages in point of simplicity, economy, durability, and general efficiency as a substitute for poultices or cataplasms of flaxseed, bread and milk, or other plastic materials, or which can be used instead of mustard or similar plasters to blister the cuticle.

Our improved remedial appliance consists of a number of small segments of metal, soapstone, or other suitable material flexibly connected together and preferably provided with a handle which enables it to be lifted, the whole forming what might be termed a "flexible dry plaster," which, being heated in any convenient way, is enveloped or covered in use to prevent it from burning the skin, and bound or laid upon the body.

The material to be used in constructing the plaster should be a good retainer of heat, due regard being had to lightness and durability. The envelope is preferably composed of three layers of material, the inside layer of asbestos paper or cloth, the middle layer of cotton-batting, and the outer layer of flannel. This envelope provides a soft covering of sufficient thickness to prevent too rapid radiation of heat to the body of the patient, and it also acts as an absorbent and retainer of the moisture exuded by the skin.

Referring to the accompanying drawings, Figure 1 shows the envelope broken away at one corner to expose a portion of the plaster or heater. Fig. 2 is a view of the plaster removed from its cover, and Fig. 3 shows the method of application to various parts of the human body.

In the drawings, A represents segments, preferably of metal or soapstone and rectangular in form, and, say, three-sixteenths of an inch in thickness. A number of these segments

are flexibly united together by metallic links B, which pass through apertures a in the segments A, and the surfaces of these segments are preferably cut away at the apertures, so that the links will not project above the surface. The number of segments used and the manner in which they are joined together will depend to a great extent upon the size and shape of the plaster which it is desired to make.

In Fig. 2 we have shown a convenient form of plaster to be applied to the stomach or chest, and in Fig. 3 we have shown plasters applied to the forehead, chest, abdomen, lower limb, and wrist.

The purpose of flexibly uniting the segments together is to adapt the plaster to be applied to any part of the body; but instead of the links shown the segments may be hinged or joined together in any other way which will permit them to be flexed in use. C represents a handle or bail applied to one edge of the plaster. The envelope shown in the drawings will be of approximately the form of the plaster and composed of three thicknesses of material, the inner thickness c being a lining of asbestos which will come in contact with the plaster, the middle layer d is of cotton-batting or other material of a fleshy nature, and the exterior layer e is preferably flannel. One end of the envelope may be closed and have the band or tape F secured thereto, and the opposite end will be open and the flaps thereof conveniently joined after the plaster is inserted by applying the ring G to one and the tape H to the other of said flaps, the tape being drawn through the opening of the ring after the plaster is inserted.

Although this plaster is applied in the dry heated state, it has been found in practice that the skin will exude sufficient moisture to produce the same beneficial effect as the wet plasters of plastic materials without the detrimental effect of soiling and wetting the clothing of the patient. Of course this dry plaster can be more quickly prepared for application and applied without soiling or wetting the clothing of the patient.

It is well known that the removal of mustard or fly plasters from the inflamed cuticle is a tedious and painful operation, and our im-

proved plaster, while equally efficient, can be removed at once and without increasing the pain. It may also be made ready for application quickly, as it can be heated by the flame of a lamp or gas-jet, or, if desired, placed directly in the fire.

We do not advise the use of this plaster to blister the skin, as we consider it preferable to use just enough heat to cause a deep reddening of the cuticle and produce irritation or itching, which can be kept up for a long period and extended over a large surface.

Without limiting our invention to the specific materials or the precise structure described, we claim—

1. A remedial appliance consisting of segments adapted to receive and retain heat and flexibly united together, substantially as described.
2. A remedial appliance for the application of heat to the human body, comprising a number of segments of a material capable of taking and retaining heat, flexibly united to each other at their margins, and an envelope or covering therefor, substantially as described.
3. A remedial appliance comprising a series of segments of material capable of taking and retaining heat and apertured at their margins and flexibly connected together and pro-

vided with a bail or handle, substantially as described.

4. A remedial appliance comprising a series of metallic segments having apertures near their margins and their surfaces cut away around such apertures, metallic links connecting the segments by being passed through said apertures, and a bail or handle applied to one of the edges of the appliance, substantially as described.

5. In combination with a remedial appliance comprising a series of segments flexibly united together, an envelope therefor composed of a plurality of folds or layers of flexible material, one of which layers is of an absorbent nature, substantially as described.

6. A remedial appliance comprising, in combination, a metallic plaster composed of a series of segments flexibly united together and an envelope therefor having an open end provided with flaps and a loop upon one end of said flaps and a tape or band upon the other adapted to be passed through the loop to close the envelope, substantially as described.

MARY FLORENCE POTTS.
JOSEPH H. POTTS.
